UNITED STATES PATENT OFFICE.

EDGAR H. ELWELL, OF DAWSON, YUKON, CANADA.

PLIERS.

1,124,118.

Specification of Letters Patent.

Patented Jan. 5, 1915.

Application filed December 2, 1913. Serial No. 804,250.

To all whom it may concern:

Be it known that I, EDGAR H. ELWELL, a citizen of the United States of America, residing at Dawson, in the Province of Yukon and Dominion of Canada, have invented 5 new and useful Improvements in Pliers, of which the following is a specification.

The present invention relates to pliers.

One of the objects of the invention is the 10 construction of a pair of pliers with a removable knife member that embodies both a longitudinal and a transverse cutting edge, whereby a fuse leading to a charge of gun powder or dynamite may be simultaneously cut transversely and slotted longitudinally to expose the powder of the fuse without permitting the said powder escaping from the fuse.

Another object of the invention is the 20 provision in a pliers of this class, of means whereby the cap may be crimped upon the fuse.

A still further object of the invention is the provision of a pliers which may be employed for splitting and cutting the ends of 25 an electric conductor wire to provide the said end with branch wires, as well as for removing the insulation from the wires.

With the above recited objects in view 30 and others which will appear as the nature of the invention is more fully understood, the improvement resides in the construction, combination and arrangement of parts set forth in the following specification and 35 falling within the scope of the appended claims.

For the purpose of illustration the accompanying drawing discloses a simple and satisfactory reduction of the improvement 40 to practise, and in which drawing:

Figure 1 is a perspective view of a pair of pliers constructed in accordance with the present invention, Fig. 2 is a central longitudinal sectional view taken through the 45 jaws of the pliers, Fig. 3 is a detail perspective view of one of the jaws, showing the knife and knife retaining plate or member removed from the jaw, and Fig. 4 is a perspective view of the second jaw.

The pliers A comprise the usual pair of 50 pivoted members, each of which including a handle and a jaw which is offset from its

handle beyond the pivotal connection between the said members, and the handles are normally swung away from each other 55 through the medium of a flat curved spring which has one of its ends secured to one of the handles and its opposite end engaging with the second handle.

One of the handles has its rounded end 60 provided with a rounded member 1, which is employed in the usual manner for forcing the powder within the casing of the fuse to provide a pocket or depression for the reception of the cap after it has been crimped 65 upon the square end of the fuse.

The jaws, which are designated by the numerals 2 and 3 respectively, are normally spaced away from each other through the medium of the spring above mentioned, and 70 each of the jaws has its inner face of a substantially similar construction. The inner faces of said jaws are flat for a portion of their length and each of said flat faces is formed with a substantially semi-cylindrical 75 transversely arranged channel or depression 4 which, when the jaws are brought together, provide a circular opening between the jaws. The sides of the jaws are projected in a line with semi-cylindrical openings 4, and these portions of the jaws are wider than at any other cross section of the said jaws. One of the enlargements, upon one side of the jaw 2 is formed by a removable plate or cap 5' which is formed 80 with a semi-cylindrical opening 5^a that is adapted to form a continuation of the semi-cylindrical depression of the said jaw. The top of the member 5' is flat and its sides are reduced from the semicylindrical end 5^a of 85 the said member, the said ends being provided with openings 5^b which are adapted to register with similar openings 5^c in the straight side of the jaw 2, the openings 5^c being threaded and retaining elements, in 90 the nature of screws 5^d pass through the registering openings 5^b and 5^c and engage with the threads of the openings 5^c. The semi-cylindrical opening 5 of the jaw 2 has the lower wall or central portion provided 95 thereby formed with a dove-tailed slot or channel B which extends the entire width of the said jaw. The slot B is adapted to receive a dove-tailed portion 7 provided upon

100

a knife member 8. The member 8 has one of its ends formed with a flat head 8' which is of a semi-circular formation and its rounded edge sharpened. The head 8' may 5 be received within a slot or depression 5° provided upon the flat side of the jaw 2, as illustrated in Fig. 3 of the drawing, but such an arrangement is not absolutely necessary, as the reduced ends of the member 10 5' will give sufficiently when engaged by the heads of the screws 5° to spring the said ends tightly against the flat face of the jaw and the central and reinforced portion of the said member 5'.
 15 The second jaw 3 is provided with a recess 10, which extends longitudinally of the said jaw, and which is adapted to serve as a pocket for the sharpened edge of the head 8' which barely enters the said recess. The 20 longitudinal portion of the knife 8 is rounded from its outer end toward the head 8', as clearly illustrated in Figs. 1 and 3 of the drawing, and to accommodate the portion of the knife at the juncture of the head 8', 25 the channel or depression 4 of the jaw 3 is provided with a slot 10' which enters the longitudinal depression or pocket 10.

The jaws adjacent their ends have their inner faces provided with curved 30 depressions, the walls of which being serrated or otherwise provided with teeth 6, the purpose of which will presently be set forth.

When the device is employed in connection with a fuse the said fuse is inserted 35 within the cylindrical depression 4 of the jaw 3, and the handles are forced together to bring the inner faces of the jaws in contact, and as a consequence, the head 8' will sever the fuse, while the knife 7' will split 40 the fuse. The ends of the jaws which are provided with the depressions having the teeth 6 are now employed for sustaining an explosive cap, which after being inserted over the square cut of the fuse, is crimped 45 by the said teeth 6, and the splitting of the said end of the fuse makes it convenient to touch a match to one of the threads of the fuse which ignites the powder in the fuse, and the said ignited powder explodes the 50 cap which in turn explodes the charge of dynamite or gunpowder to which the fuse leads.

When the device is employed for splitting the ends of an electric wire conductor, the 55 said conductor is inserted within the recessed or depressed portions 4 of the jaw 3, and the handles swung together to bring the knife into engagement with the fuse, the said engagement cutting the fuse trans- 60 versely as well as slitting the same longitudinally, and the said slit splits the conductor and forms the same with two branch wires to which additional connecting wires may be attached.

65 From the above description, taken in con-

nection with the accompanying drawings, the simplicity of the device as well as the advantages thereof will, it is thought, be perfectly apparent to those skilled in the art to which such inventions appertain without 70 further detailed description.

Having thus described the invention, what I claim is:

1. Pliers for the purpose set forth comprising a pair of pivoted members including 75 spring pressed handles and a jaw provided for each of the handles, each of the jaws having a flat inner face, the jaws on the said inner face being provided with alining semi-circular depressions and having their 80 sides enlarged to provide extensions which surround the depressions, one of the said enlargements being removable, the depression provided upon the jaw with the removable enlargement having a slot, a knife 85 member adapted to be arranged within the slot, said knife member including a semi-circular head which is arranged transversely of the knife proper and which is adapted to abut against the flat side of the jaw, means 90 for securing the removable member to the jaw, and the said removable member adapted to contact with the outer face of the rounded head of the knife.

2. Pliers for the purpose set forth, comprising a pair of pivoted members which include spring pressed handles and a jaw formed upon each of the handles, each of said jaws having an inner flat face which is recessed transversely to provide a semi-circular depression, the jaws having their sides provided with enlargements which are also depressed, one of the said enlargements being removable, the jaw provided with the removable enlargement having the wall of 105 its depression centrally formed with a longitudinally extending dove-tailed slot and its flat side recessed, the said recessed portion communicating with both the depression and dove-tailed slot, a knife member 110 having a dove-tailed end adapted to be inserted within the dove-tailed slot, the said member being provided with a transversely arranged head which is adapted to be received within the depression in the side of 115 the jaw, and means comprising removable elements for securing the removable enlargement to the jaw.

3. Pliers comprising a pair of pivoted members including spring pressed handles 120 and a jaw formed upon each of the handles, each of said jaws having an inner flat face which is recessed to provide a transverse semi-circular depression, the opposite faces of the jaws having extensions which surround their depressions to provide extensions for the said depressions, the said depressions adapted to register when the jaws are brought together, each of the jaws being provided with longitudinally extending 125 130

slots, a knife member secured longitudinally of and centrally within one of the depressions, a knife head having a curved edge and secured to one end of the knife member 5 transversely thereof, the registering depression of the other jaw adapted to receive the knife member and its head when the jaws are closed, and the reduced ends of the jaws

having arcuate depressions which are toothed. ¹⁰

In testimony whereof I affix my signature in presence of two witnesses.
